(57) **CLAIM**

The ornamental design for a credit card-sized personal computer with wireless communication, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a top perspective view of the credit card-sized personal computer with wireless communication showing my new design.

FIG. 2 is a front view thereof.

FIG. 3 is a top view thereof.

FIG. 4 is a right side elevational view thereof; the left side is symmetrical.

FIG. 5 is a bottom view thereof; and,

FIG. 6 is a rear elevational view thereof.

The broken lines are shown in FIG. 1 for illustrative purposes only and form no part of the claimed design.
